APPROACH CONTROL APPARATUS FOR
RAILWAY SIGNALING SYSTEMSEdward U. Thomas, Pittsburgh, Pa., assignor to
The Union Switch & Signal Company, Swiss-
vale, Pa., a corporation of Pennsylvania

Application July 26, 1938, Serial No. 221,317

25 Claims. (Cl. 246—38)

My invention relates to approach control apparatus for use in railway signaling systems of the coded track circuit class and it has special reference to the employment of such apparatus for approach controlling various signaling functions without the use of line wires.

Generally stated, the object of my invention is to improve certain features of an approach control without line wire scheme wherein the 10 rails of each unoccupied signal block length of track transmit code step pulses of auxiliary energy forwardly from the block entrance to effect the energization of a slow release approach relay at the block exit.

15 A more specific object is to provide improved means for detecting these pulses at the exit end of the track circuit and for energizing the associated slow release approach relay in step with these pulses.

20 Another object is to prolong each period of this relay energization for the full duration of the signal code "off" period within which it occurs.

An additional object is to quicken the response of the approach relay to a shunting of the track 25 circuit to such an extent that cab signal flips at block joints will be avoided.

A further object is to detect the absence of received auxiliary energy within the space of a single code cycle.

30 A still further object is to effect the above through the use of circuit means of comparative-
ly simple character.

In practicing my invention I attain the above and other objects and advantages by introducing the pulses of auxiliary energy into the track circuit during the "off" periods of the main signal control code; by providing the exit end of the track circuit with a sensitive code following detector relay which receives these auxiliary energy 40 pulses from the track rails and which causes the associated slow release approach relay to be energized in step with them; by providing the detector relay with a stick circuit which prolongs the hold-up time of that relay for the full duration of each of the "off" periods of the signal control code within which that relay responds; and by supplying the approach relay with supplementary energizing pulses during the "on" code periods.

50 I shall describe a few forms of approach controlling apparatus embodying my invention and shall then point out the novel features thereof in claims. These illustrative embodiments are disclosed in the accompanying drawings, in
55 which:

Fig. 1 is a diagrammatic representation of a section of railway track which is equipped with one preferred form of my improved approach control apparatus;

Fig. 2 is a partial representation of the exit end 5 facilities of Fig. 1 arranged in a slightly modified manner;

Fig. 3 is a code cycle diagram which is identified with Figs. 1 and 2;

Fig. 4 is a diagrammatic view of exit end fa- 10
cilities which employ a code following detector
relay having but a single winding; and

Figs. 5 to 9 inclusive are similar showings of 15
exit end facilities which use double winding de-
tector relays and which supply the approach re-
lays with supplementary energizing pulses dur-
ing the "on" periods of the signal control code.

In the several views of the drawings, like ref-
erence characters designate corresponding parts. 20
Referring first to Fig. 1, the improved approach
control apparatus of my invention is there dis-
closed in association with a coded track circuit
system of automatic block signaling for a rail-
way track 1—2 over which it will be assumed 25
that traffic moves in a single direction indicated
by the arrow, or from left to right in the diagram.
The protected stretch of this track is divided into
the customary successive sections by insulated
rail joints 3 and the rails of each section form a
part of a track circuit to which coded signal 30
control energy is supplied in customary manner.

In Fig. 1, reference characters D and E re-
spectively designate the entrance and exit ends 35
of one of these track sections which is illustrative-
ly shown as being a full signal block in length; 35
character TR designates a code following track
relay which is installed at the entrance end of
the section and operated by energy received from
the rails thereof; character TB a track battery or
other direct current source provided at the sec- 40
tion exit for the purpose of supplying these rails
with the relay operating energy just referred to;
character CR a coding device having a contact 5
which codes this energy by periodically inter-
rupting the rail supply circuit; and character S 45
the usual wayside signal which guards the en-
trance of each of the track blocks and which is
controlled by the associated track relay TR
through the medium of decoding apparatus 10.

The referred to coded track circuit system of 50
automatic block signaling operates without the
aid of line wires and includes all of the elements
above named. Further comprised by the system
are the customary facilities (not shown) for con-
tinuously operating each of the exit end relays 55

CR at one or another of the usual plurality of distinctive code rates. In a typical three-indication system, two such rates are employed and ordinarily these will consist of 75 and 180 energy pulses per minute. Selection among the rates of signal control code is made in accordance with advance traffic conditions by the decoding apparatus 19 functioning in customary manner.

This decoding apparatus (details not shown) is controlled in the usual fashion by the associated track relay TR and it performs the further function of selectively setting up a lighting circuit for one or another of the lamps (G, Y and R in the typical three-indication system above referred to) 15 of the wayside signal S at the same location. In the arrangement represented these signal lamps derive energizing current from a power source which is designated by the terminals "plus" and "minus."

20 For applications in which train carried cab signals (not shown) also are to be controlled, the representative coded signaling facilities still further comprise means at the exit end of the track circuit for additionally supplying the rails thereof 25 with coded alternating current energy. In the form shown at location E in Fig. 1, these means include a track transformer TT having a secondary winding which is connected with the track rails over coding contact 5 of device CR 30 during each "energy on" period of the signal control code from battery TB. At proper times the primary winding of this transformer is energized over a conductor 7 from a suitable alternating current source designated by the terminals B 35 and C.

In order that certain functions of the signaling system may be rendered active only upon the approach of a train, the apparatus installed at each of the signal locations D, E etc. is supplemented by an approach relay AR which is arranged to maintain the referred to functions inactive at all times except when the section of track to the rear of the location becomes occupied. In the illustrative arrangement which is 40 shown at location E in Fig. 1, these approach controlled functions consist in lighting the wayside signal S (normally dark) and in supplying the rails of the track section to the rear of that signal with alternating current energy for cab signal control.

50 The former function is governed by a contact 9 of the approach relay AR and the latter by a companion contact 11 thereof. Either of these functions may, of course, be controlled individually by 55 the approach relay AR, and it will be apparent, moreover, that signaling functions other than or in addition to those just named may likewise be governed by the same relay.

When applied to coded signaling systems of the 60 conventional character just considered, the improved approach control apparatus herein disclosed renders the relay AR at each signal location responsive to the approach of a train and does this, moreover, without the use of control line 65 wires.

For each of the signal blocks this approach control apparatus comprises: (1) entrance end facilities which supply the rails of that block with pulses of auxiliary energy which are in step with 70 recurring periods of the signal control code; and (2) exit end facilities which receive these auxiliary pulses from the rails and energize the approach relay AR in step with them.

In the form shown at location D in Fig. 1, the 75 entrance end facilities are the same as those dis-

closed and claimed by a copending application of Herman G. Blosser, Serial No. 222,014, filed July 29, 1938, and assigned to The Union Switch & Signal Co. These include a battery or other source of auxiliary energy AB, an impulse relay 5 IR which transfers the connection of the track rails 1 and 2 from the track relay TR to battery AB during each "off" period of the signal control code, and a transformer IRT which supplies relay IR with a pulse of pick-up energy at the beginning 10 of the "off" code periods.

Transformer IRT is provided with a direct current exciting circuit which includes, in the particular form shown, a back contact 12 of relay TR and which is completed each time that the track 15 relay releases. The resulting build-up of primary current causes the transformer to induce in its secondary winding a pulse of voltage (an equivalent effect may be produced by interrupting instead of completing the transformer exciting circuit 20 upon each track relay release) having the polarity indicated by the vertical arrow. This is impressed upon the operating winding of the impulse relay IR and causes the relay to respond. The relay IR is of the polar type and contact 13 25 thereof occupies the lowermost position shown in full line as long as the relay remains deenergized or receives current of reverse relative polarity. In that position it connects the operating winding of the track relay TR directly across the track 30 circuit rails 1 and 2.

When, however, relay IR receives from transformer IRT the beforementioned pulse of normal polarity energy it biases contact 13 upwardly into the dotted position and thereby disconnects 35 relay TR from the track rails and instead connects auxiliary battery AB thereacross. In this manner each release of the track relay TR causes the impulse relay IR momentarily to transfer the track rail connection from the winding of relay 40 TR to the output circuit of battery AB. Due to the momentary character of the normal polarity output pulse from transformer IRT at the beginning of each of the "off" periods of the signal control code, the duration of each of these connection 45 shifts is comparatively short.

In the form shown at location E in Fig. 1, my improved exit end facilities comprise a detector relay KR2 which responds to pulses of auxiliary energy received over the rails 1 and 2 from battery 50 AB, a circuit controlled by contact 15 of that relay for locally energizing the approach relay AR from a source designated by the terminals "plus" and "minus", means for making the relay AR sufficiently slow releasing to bridge the intervals 55 between recurrent responses of the detector relay, and a stick circuit for the detector relay KR2 controlled over a contact 16 thereof and effective to prolong the hold-up time of the relay for the full duration of the "off" periods of the signal control code which coding contact 5 of device CR 60 produces.

This detector relay KR2 is of the code following type and the represented interposition thereof between the slow release approach relay AR and the track rails is similar to that disclosed and claimed in each of the following two copending applications: Serial No. 220,015 filed July 19, 1938, by Crawford E. Staples and Serial No. 223,076 filed August 4, 1938, by Herman G. 70 Blosser. In the form shown in Fig. 1 this detector relay is provided with separate pick-up and stick windings 17 and 18. The pick-up or operating winding 17 is connected in energy receiving relation with the track rails 1 and 2 only 75

5 during the "off" periods of the signal control code. This connection is completed by coding contact 5 when in its lowermost or released position. The stick winding 18 of the relay KR2 is energized from a suitable local source, designated by the terminals "plus" and "minus", over a circuit which is set up by a second contact 19 of the coding relay CR (contacts 5 and 19 shift their positions simultaneously) and which is completed 10 by the aforementioned front contact 16 of the detector relay KR2.

10 The slow release approach relay AR may be energized in step with the responses of the detector relay KR2 in any suitable manner. As 15 shown in Fig. 1, a transformer AT is interposed between the winding of relay AR and a local source of direct current supply. The primary circuit of this transformer is pole changed by contact 15 of the detector relay in well-known 20 manner and the output energy from the transformer is supplied to the operating winding of relay AR over circuits which include a rectifying contact 21 of detector relay. This particular arrangement of devices KR2, AT and AR embodies principles that are disclosed and claimed in a copending application Serial No. 210,744 filed May 28, 1938, by Frank H. Nicholson et al. As 25 shown in Fig. 2, a somewhat simpler though generally equivalent arrangement includes the contact 15 of the detector relay directly in the circuit of the operating winding for the approach relay AR. Both of these arrangements function 30 to supply pulses of pick-up energy to the approach relay only when the detector relay KR2 is following code.

35 In operation of the complete approach control system shown in Fig. 1, the track rails 1 and 2 of section D—E act in the usual manner to transmit energy from one end of the section to the other as long as the section remains unoccupied. 40 Each time, under such conditions, that contact 5 of the coding device CR is in the picked-up or "on" code period position the track battery TB picks up the track relay TR over a circuit which 45 may be traced from the positive terminal of the battery through a current limiting impedance 22, front contact 5 of device CR, conductor 23, track rail 1, conductor 24, the winding of relay TR, conductor 25, back contact 13 of impulse relay IR, conductor 26, track rail 2, conductors 27 and 50 28, the secondary winding of transformer TT and conductor 29 back to the negative terminal of the battery TB.

55 Each time that the coding contact 5 occupies the released or "off" code period position and connects the pick-up winding 17 of the detector relay KR2 across the track rails, the track relay TR at the entrance end of the section releases and contact 12 thereof completes for the transformer IRT the aforementioned exciting circuit which may be traced from the positive terminal of a suitable supply source through back contact 12, conductor 31 and the primary winding of the transformer back to the negative terminal 60 of the supply source. This excitation induces in the secondary winding of the transformer a pulse of normal polarity voltage which picks up the impulse relay IR over a circuit extending from the upper terminal of the transformer 65 secondary through conductor 32, the winding of relay IR, and conductor 33 back to the lower terminal of the transformer secondary.

70 This energization of relay IR occurs at the beginning of each of the "off" periods of the signal control code. In responding, contact 13 of relay

IR momentarily picks up and disconnects the winding of relay TR from the track rails and connects the auxiliary battery AB thereacross. Under this condition the battery picks up the detector relay KR2 at the exit end of the section over a circuit which may be traced from the positive terminal of battery AB through a current limiting impedance 35, front contact 13 of relay IR, conductor 26, track rail 2, conductor 27, the winding 17 of relay KR2, conductor 36, back contact 5 of device CR, conductor 23, track rail 1, and conductors 24 and 37 back to the negative terminal of battery AB.

75 Under the influence of each of these auxiliary pulses of energy thus received from the track-way, the code following detector relay KR2 picks up and contact 15 thereof causes the operating winding of the approach relay AR to be supplied with a corresponding pulse of local pick-up energy. In addition, contact 16 of the detector relay completes the aforementioned stick circuit through which winding 18 of the relay is energized until the end of the "off" period of the signal control code. In the form shown in Fig. 1, this now completed stick circuit may be traced from the positive supply terminal through front contact 16 of relay KR2, conductor 39, back contact 19 of device CR, and the relay winding 18 back to the negative supply terminal.

80 The resulting recurring pulses of local energization which are supplied over contact 15 of the detector relay to the slow release approach relay AR cause the approach relay to hold its contacts 9 and 11 continuously picked up, thereby 85 maintaining the wayside signal S and the track transformer TT at location E deenergized as long as the track section D—E remains vacant. They referred to slow releasing characteristic of relay AR may, of course, be imparted in any one of a number of well-known manners, such as by internal design expedients or the use of an external snubbing impedance (not shown).

90 Assume, now, that a train comes into the track section D—E. The usual shunting action of its wheels and axles reduces to a very low value the 95 potential difference between the rails 1 and 2 and thus deprives both of the relays TR and KR2 of pick-up energy. Relay KR2 now remaining continuously released, the supply of local energization to the approach relay AR is discontinued. In consequence, that relay now completes at contacts 9 and 11 the energizing circuits 100 for signal Se and transformer TT at location E.

105 As a result the named wayside signal now lights the particular lamp selected by the decoding equipment 10 and the transformer TT supplies the rails of track section D—E with a pulse of alternating current energy from a source B—C each time that the contact 5 of device CR occupies its uppermost position. As has been 110 mentioned, this energy is suitable for the control of cab signals which may be carried by the train proceeding through the track section and the circuit over which it is supplied may be traced from the right terminal of the secondary winding 115 of transformer TT through conductor 29, battery TB, impedance 22, front contact 5 of device CR, conductor 23, track rail 1, the wheels and axles (now shown) of the train, rail 2 and conductors 27 and 28 back to the left terminal of the track 120 transformer secondary.

125 In the particular form shown in Fig. 1 the primary circuit for transformer TT is controlled by contact 11 of the approach relay AR in such manner that when the relay is released the pri- 130

- mary of the transformer is connected with the terminals B and C over back contact 11, conductor 7 and conductor 40. When, however, the contact 11 is picked up the connection just named is broken and the two terminals of the primary winding of transformer TT are bypassed over a circuit which extends from the right terminal thereof through conductor 40, front contact 11 and conductor 7 back to the left terminal. The purpose of this by-pass is to reduce the impedance which the secondary winding of the transformer presents to the flow of direct current from battery TB to the track rails under conditions of track section vacancy.
- As soon as the rear of the departing train clears the exit end of location E the coded direct current energy from track battery TB is again transmitted by the rails to the track relay TR at the entrance location D. That relay once more responds and the operation of contact 12 thereof causes the impulse relay IR again to connect the track rails in energy receiving relation with the auxiliary battery AB during each of the "off" code periods. These pulses of auxiliary energy from battery AB are, in turn, transmitted by the rails to the detector relay KR2 at the exit location E. In responding to them that relay again causes the approach relay AR to receive recurrent pulses of local energizing current. Relay AR once more picks up and due to its slow release characteristics continuously de-energizes the wayside signal Se and the track transformer TT at location E, thereby restoring both of these devices to their normally inactive states.
- The approach control facilities shown in Fig. 1 are of particular advantage in coded signaling systems wherein train carried cab signals as well as wayside signals S are to be controlled. In such cab signaling applications time or quickness of response by the slow release approach relay AR is an important factor, for when the cab signal energy is applied after the entrance of the train into the track circuit it is desirable that this energy be made available soon enough to avoid "flip" or momentary false "stop" indications by the cab signals when the train vehicle on which they are carried passes over the insulated rail joints 3 at the track circuit entrance.
- Generally speaking, the less the time that is required for introducing the alternating current cab signal control energy into the track circuit, the less will be the chance for this undesirable cab signal flip. Hence, detection of the entry of the train into the track circuit within the shortest time practicable is the operating condition most desired.
- In an approach control without line wire scheme of the type shown in Fig. 1, however, the quickness with which this cab signal control energy may be applied to the track circuit following the entry of a train therein is, of course, limited by the release delay period of the approach relay AR. This period, in turn, can never be reduced beyond the time required to span the spacing between the recurring energy pulses which are locally supplied to the operating winding thereof under the control of the code following detector relay KR2.
- The spacing between these recurring pulses is, of course, greatest for the lowest code which the signaling system employs for signal control purposes, and an approach relay AR which is sufficiently slow in releasing to remain continuously picked up when the vacant track circuit is re-

ceiving this slowest code will operate properly for all other codes having a higher rate of energy pulse recurrence. Thus, in the case of the typical three-indication system assumed to employ two codes of 75 and 180 energy pulses per minute, the conditions present when the 75 code is being introduced into the track circuit are those which must be considered in fixing the minimum period of delay release for the approach relay AR at the exit end of each track section.

It has been pointed out that the impulse relay IR at the entrance end of the section picks up only momentarily at the beginning of each "off" period of the signal control code and thus causes the track circuit to receive a comparatively short pulse of auxiliary energy from the battery AB. Some idea of the comparative length of this pulse in relation to the cycle periods of the signal control code may be gained from an inspection of the diagram of Fig. 3.

In Fig. 3 the length of the auxiliary energy pulses is designated by the character k . This time corresponds to that during which the contact 13 of relay IR is picked up during each of the "off" periods of the main signal control code supplied from battery TB over coding contact 5 of relay CR at the exit location E and responded to by the track relay TR at the entrance location D. When the highest speed code which the signaling system employs consists of 180 energy pulses per minute as previously assumed, the time represented by k may be as small as $\frac{1}{100}$ second. This shortness is necessary to prevent overlapping of the auxiliary energy pulse ("off" code period) with adjacent "on" periods of the named highest speed (180 or other) code of the signaling system.

To aid explanation, the diagram of Fig. 3 has been drawn on the basis of a signal control code having the assumed slower rate of 75 pulses per minute. Such a code is made up of recurring cycles each consisting of an "off" period having a length of approximately $\frac{1}{6}$ second and an "on" period of about the same length. This means that each cycle of the 75 code has a total duration of $\frac{1}{6}$ of a second. These periods are substantially longer than those of the higher speed code of 180 energy pulses per minute, the cycles of which have a total length of $\frac{1}{3}$ second and the "on" and "off" periods of approximately $\frac{1}{6}$ second each.

Were the detector relay KR2 at the exit location E to be operated solely by the auxiliary energy received over the rails 1 and 2 from the entrance end facilities, it would be necessary to design the approach relay AR for a release period of the order designated at b in Fig. 3. For a signal control code of 75 energy pulses per minute this is only slightly less than $\frac{1}{6}$ second total cycle length. Assuming that the auxiliary energy pulse has a length of $\frac{1}{100}$ second (the before stated value for k of Fig. 3) the approach relay AR must be designed with a delay of not less than $\frac{7}{100}$ second, and is preferably of the order of one full second to provide for proper operating margins.

This means that at least one second will elapse from the time that a train first comes into section D-E until contact 11 of the relay releases and supplies alternating current energy from source B-C to the rails over coding contact 5. Train 70 carried cab signals of conventional design are found to display the "stop" indication when the control energy therefor is interrupted for a period of this comparatively long character, and in this respect the assumed use of the auxiliary energy

only to operate the detector relay **KR2** produces a defective form of approach control operation.

In my improved exit end facilities which are represented at location E in Fig. 1, this effect is overcome by providing the detector relay **KR2** with the beforedescribed "stick" circuit which prolongs the hold-up time of this relay for the full duration of the signal code "off" period within which the relay response occurs. The substantial order of this hold-up extension is indicated at c in Fig. 3. Instead of releasing at the end of the auxiliary energy pulse supplied over the track rails to the pick-up winding **17**, the contacts of relay **KR2** are maintained picked up by the stick winding **18** which continues to receive energy over front contact **16** and back contact **19** of code device **CR** until the end of the "off" period, at which time the coding contact is moved to its uppermost position for producing another "on" code period.

This means that the periods of recurrent energization of the slow release approach relay **AR** are correspondingly extended to a value of the order indicated at e in Fig. 3. When the relay employs the directly controlled energizing scheme shown in Fig. 2, the direct extension indicated in Fig. 3 applies. When the relay control scheme involves an interposed transformer of the character shown at AT in Fig. 1, comparable improvements also are realized and in addition distorted "on" time operation of the coding device contacts, **15** and **21** is prevented from interfering with the desired continuous response of the approach relay.

In both cases the minimum period of release for the approach relay **AR** is reduced from value **b** to the much shorter time designated by character **d** in Fig. 3. For the 75 energy pulse per minute code, on the basis of which Fig. 3 has been drawn, it will be seen that the reduced minimum delay period is only slightly greater than half as much as the minimum delay period when the detector relay **KR2** is not provided with the stick circuit herein disclosed. In practical terms, this means that the approach relay **AR** now needs be designed to have a contact release period of only $\frac{1}{10}$ second as compared with the previous minimum of one full second or greater.

On the 180 or other higher energy pulse per minute code, the use of a detector relay **KR2** having my improved stick circuit results in comparable reduction in the spacing between consecutive pulses of energization which contact **15** causes to be supplied to the operating winding of the approach relay **AR**. For all codes, therefore, the effect is substantially to lengthen the periods of approach relay energization and to make possible the reproduction of very nearly equal "on" and "off" code step times (when device **CR** produces equal "on" and "off" periods) of relay energization. As long as the initiating pulses of auxiliary energy from battery **AB** occur shortly after the release of the coding contact **5** of device **CR** this approximate equality will be maintained.

Although the initiating pulses may be of finite length (designated at **k** in Fig. 3) the just stated relation will be maintained for each and every one of the different signal control codes (assumed to be of 75 and 180 energy pulses per minute for a three-indication system) which the coded signaling system employs. Moreover, the nature of the stick circuit with which relay **KR2** is provided is such that variations in the absolute length of these auxiliary energy pulses do not interfere with the operation just described.

Referring now to Fig. 4 I have there repre-

sented a somewhat modified form of exit end facilities which correspond to those shown at location E in Fig. 1. Structurally, the facilities of Fig. 4 differ from those of Fig. 1 in that use is made of a code following detector relay **KR** having but a single winding which is arranged to perform both the pick-up and the stick functions.

As in the system of Fig. 1, the pick-up current is received from the entrance end facilities (not shown in Fig. 4 but corresponding to those shown at location E in Fig. 1) over the rails **1** and **2** during the "off" periods of the signal control code which is produced by contact **5** of the device **CR**. In Fig. 4, however, another contact **42** (corresponding to **19** of Fig. 1) is employed by the coding device and the track battery **TB** is employed as the source of stick current for the detector relay **KR**. This stick current is transmitted from battery **TB** to the winding of detector relay **KR** whenever contact **16** of that relay is picked up at a time that contact **5** of device **CR** is in the lowermost or "off" code period position. Contact **15** of this detector relay controls the energizing circuit for the slow release approach relay **AR** in the same manner as shown in Fig. 2, that is, each time that relay **KR** picks up relay **AR** is energized over a circuit which extends from the positive terminal of a suitable supply source through front contact **15** of relay **KR**, conductor **41**, and the operating winding of relay **AR** back to the negative terminal of the supply source.

In addition to controlling the circuit through which the before referred to stick current is transmitted, contact **16** of relay **KR** forms a part of the circuit over which pick-up current is supplied to the relay winding from the track rails. In the arrangement of Fig. 4, as in that of each of Figs. 1 and 2, the approach relay **AR** is provided with contacts **9** and **11** which control the wayside signal **Se** and the track transformer **TT** at location E in the manner previously explained in detail.

In operation of the approach control facilities shown in Fig. 4, the track rails **1** and **2** of the section to the rear of location E act in the usual manner to transmit energy from one end of the section to the other as long as the section remains vacant. Each time, under such conditions, that the contacts of the coding device **CR** are in the uppermost position, the track battery **TB** supplies these rails with a pulse of track relay operating energy over a circuit which may be traced from the positive terminal of the battery through front contact **5** of relay **CR**, conductor **23**, track rail **1**, the winding of relay **TR** (not shown in Fig. 4), track rail **2**, conductor **27**, front contact **42** of device **CR**, conductor **43**, the secondary of track transformer **TT**, and current limiting impedance **22** back to the negative terminal of battery **TB**.

Each time that the contact of coding device **CR** occupies the lowermost position, the track relay **TR** (see location D of Fig. 1) releases and causes impulse relay **IR** (again see Fig. 1) to pick up its contact **13** and thereby momentarily connect the associated auxiliary battery **AB** with the track rails. Under this condition the winding of detector relay **KR** receives a pulse of auxiliary energy over a circuit which may be traced from the positive terminal of battery **AB** (see Fig. 1) through front contact **13** of relay **IR**, conductor **26**, track rail **2**, (see Fig. 4), conductor **27**, back contact **42** of device **CR**, conductor **45**, the wind-

ing of relay KR, conductor 46, back contact 16 of relay KR, conductor 23, track rail 1 and conductors 24 and 37 (again see Fig. 1) back to the negative terminal of battery AB.

- 5 Under the influence of each of these auxiliary energy pulses, the code following detector relay KR picks up and thus completes the local energizing circuit for the slow release approach relay AR at contact 15 and its own stick circuit at 10 contact 16. This stick circuit may be traced from the positive terminal of track battery TB through back contact 5 of device CR, conductor 47, the winding of relay KR, conductor 46, front contact 16 of relay KR, and a current limiting 15 impedance 48 back to the negative terminal of battery TB. The intensity of the pick-up energization for the relay AR is so chosen that the relay armature moves the contact 16 completely from the back to the front position due to the 20 momentum which is produced by the initial surge of auxiliary trackway energy over the back contact 16.

As in the facilities of Fig. 1, the above traced stick circuit maintains the relay KR picked up 25 until the circuit is broken by movement of contact 5 of device CR to the uppermost position at the end of the "off" code period. The circuit, moreover, is so connected with battery TB that the polarity of energy which is supplied to 30 its winding KR is the same as that of the auxiliary energy received over the rails 1 and 2 from the entrance end facilities (not shown in Fig. 4).

Each time that contact 15 of relay KR is thus 35 picked up, it completes for the approach relay AR an energizing circuit already described as including conductor 41.

Under the influence of the recurring pulses of 40 this energization this slow release relay AR holds its contacts 9 and 11 continuously picked up and thereby maintains the wayside signal S and the track transformer TT at location E deenergized as long as the track section to the rear of that 45 location remains vacant.

Assume now that a train comes into the track 45 section just referred to. The usual shunting action of its wheels and axles reduces to a very low value the potential difference between the rails 1 and 2 and thus deprives the detector relay KR of pick-up energy. Now remaining continuously released, contact 15 of that relay continuously 50 interrupts the energizing circuit for the slow release approach relay AR. That relay now releases and completes at contacts 9 and 11 the energizing circuits for signal Sc and transformer TT.

In consequence, the named wayside signal 55 lights the particular lamp selected by the decoding equipment and transformer TT supplies the track rails with pulses of alternating current energy from source B-C each time that the contacts of device CR occupy their uppermost 60 positions. This cab signal control energy is supplied over a circuit which may be traced from the upper terminal of the secondary winding of 65 transformer TT through impedance 22, track battery TB, front contact 5 of device CR, conductor 23, track rail 1, the wheels and axles (not shown) of the train, rail 2, conductor 27, front contact 42 of device CR, and conductor 43 back to the 70 lower terminal of the transformer secondary.

As soon as the rear of the departing train clears 75 the exit end of location E the coded energy from track battery TB is again transmitted by the rails to the track relay TR at the entrance end of the section. That relay once more responds and

causes the track rails 1 and 2 again to be supplied with code step pulses of auxiliary energy. These in turn are transmitted to the detector relay KR at the exit location E and in responding to them the contact 15 thereof once more recurrently completes the energizing circuit for the approach relay AR. That relay again picks up and due to its slow release characteristics continuously deenergizes the wayside signal Se and the track transformer TT at location E, thereby restoring both of these devices to their normally inactive state.

From the standpoint of operation the facilities of Fig. 4 are the full equivalent of those shown at location E in Fig. 1. Both function to prolong 15 each period of pick-up of the code following detector relay KR for the full duration of the signal code "off" period within which the pick-up action occurs and they thus permit the release period of the approach relay AR to be reduced to the 20 extent that the approach relay may respond to a shunting of the track circuit with a quickness sufficient to avoid cab signal flips at block joints.

Each of the embodiments of my invention so far described incorporates means for obtaining 25 very nearly equal "on" and "off" periods (when the signal control codes produced by device CR have equal "on" and "off" times) of energization for the slow release approach relay AR when controlled by the code following detector relay AR 30 in response to code step pulses of auxiliary energy received from the trackway. This substantial equality of "on" and "off" periods is maintained, moreover, over a wide range of code speeds even though the duration of the auxiliary energy 35 pulses may be the same for all of the several codes. In that event, of course, the duration of the auxiliary energy pulse is the same for each operation of the impulse relay IR at the entrance end of location D but occurs at different intervals 40 in accordance with the spacing of the energy pulses of the main signal control code supplied to the rails at the exit end location E over the continuously operating contact 5 of the coding device CR.

In addition to obtaining the "on" time correction feature in the detector relay KR, I am 45 able definitely to detect the absence of an auxiliary energy pulse in a single code cycle and I obtain this detection by further application of 50 the basic stick circuit arrangement disclosed in Figs. 1, 2 and 4 for the code following detector relay KR. Circuits showing various means for detecting an omission of the auxiliary pulse within one code cycle are shown in each of Figs. 55 5 to 9 inclusive.

The desirability of such detection is to provide 60 further assurance against the giving of undesirable cab signal flips at block joints. Generally speaking, it is desirable that the detection be quickened at the higher code speeds. Moreover, the less time required to introduce the new codes as the train first enters each track circuit, the less chance there will be for a cab signal flip to occur. In all events, it is desirable to detect the entry of 65 a train into the track section within one code cycle, since this positively assures that the higher the signal control code the lower the detecting time will be. For example, in the case of the 70 75 pulse per minute code represented in Fig. 3 the maximum detecting time will be $\frac{1}{10}$ second (the code cycle length) and for the previously described 180 pulse per minute code the maximum time will be reduced to the smaller code cycle length of $\frac{3}{10}$ second.

Referring to Fig. 5, I have there represented exit end facilities for an approach control without line wire scheme of the general character described in connection with track section D—E of Fig. 1. These facilities cooperate with the constantly operating coding device CR which is arranged repeatedly to connect the track rails 1 and 2 of the section to the rear of location E first with the track battery TB and then with the pick-up winding 17 of the code following detector relay KR2. The arrangement of coding contact 5 of device CR differs from that shown in Fig. 1 in that the track battery connection is established when the contact is in its lowermost position and the relay winding is established when the contact is in its uppermost position. The two arrangements are, however, interchangeable and hence either may be used. In the case of both the coding device CR operates continuously under ordinary conditions.

The detector relay KR2 is represented as being a duplicate of the correspondingly designated device of Fig. 1. It is provided with a separate stick winding 18 which following each response of the relay is supplied with energizing current over front contact 16 of relay KR2 and front contact 19 of coding device CR. This stick circuit is interrupted at contact 19 at the end of each "off" period of the signal control code from battery TB.

The slow release approach relay shown at AR1 in Fig. 5 also may be a duplicate of the device AR of Fig. 1 with the exception that the period of its release delay need not be as great. Its energizing circuit is completed over front contact 15 of detector relay KR2 in the same manner as in Fig. 2. In addition, the relay AR1 is provided with a supplementary energizing circuit which is set up by a front contact 50 of the relay and which is completed over a conductor 51 each time that the contact 19 of the coding device CR occupies the lowermost or "on" period position of the main signal control code. As in Fig. 1, this approach relay AR is provided with contacts 9 and 11 which respectively control the wayside signal Se and the connection of transformer TT at location E with the alternating current source B—C.

Whereas in the schemes of Figs. 1, 2 and 4 the approach relay AR must be designed with a release delay period sufficient to span the spacing between consecutive pick-ups of contact 15 of the detector relay KR2, in the arrangement of Fig. 5 a much smaller period of release delay is adequate due to the supplementary energization supplied over back contact 19 of the coding device CR and front contact 50 of the relay AR. The length of this reduced delay need only be sufficient to span the time required for contact 19 of device CR to move from the lowermost to the uppermost position plus that for detector relay KR2 to pick up contact 16 in response to a pulse of auxiliary energy received from the track rails. The absolute magnitude of the named period is comparatively small and does not materially change for different rates of signal control code which contact 5 of device CR produces.

For the purpose of assuring quick response of the approach relay AR it is desirable to limit its release delay period to a value only sufficiently greater than that just stated to assure that the relay will not flip. For approach control systems of the type now under consideration a release delay value of the order of $\frac{1}{16}$ second will ordinarily

be adequate. This, it will be noted, is substantially less than the 33/100 second cycle length for the 180 pulse per minute code previously referred to.

In explaining the operation of the approach control facilities of Fig. 5, assume that the rails 1 and 2 extending rearwardly from the exit location E are connected with entrance end facilities of the character represented at location D in Fig. 1. Under all traffic conditions of the track section D—E, device CR of Fig. 5 continuously operates its contacts. Contact 5 thus repeatedly connects the rails 1 and 2 first with the track battery TB and then with the pick-up winding 17 of the detector relay KR2 and contact 19 likewise repeatedly connects the "plus" power source terminal first with the approach relay circuit conductor 51 and then with the detector relay stick circuit.

As long as the section remains vacant the track battery TB at location E thus supplies the operating winding of the track relay TR at location D with recurring pulses of pick-up energy. The winding supply circuit which is effective during each "on" period of this direct current trackway code may be traced from the positive terminal of the track battery through current limiting impedance 22, back contact 5 of device CR, conductor 23, track rail 1, conductor 24, (see Fig. 1), the winding of relay TR, conductor 25, back contact 13 of relay IR, conductor 26, track rail 2, (see Fig. 5), conductor 27 and the secondary of transformer TT back to the negative terminal of the track battery TB.

In this manner the track relay TR is caused to pick up its contacts upon the occasion and for the duration of each of the "on" periods of the signal control code. During the "off" periods which intervene it releases in the manner already explained in the description of Fig. 1 and causes the impulse relay IR momentarily to connect the auxiliary battery AB in energy supplying relation with the rails 1 and 2. These rails transmit a pulse of pick-up energy to the winding 17 of the detector relay KR2 at location E. The winding supply circuit now effective may be traced from the positive terminal of battery AB at location D (see Fig. 1) through impedance 35, front contact 13 of relay IR, conductor 26, the track rail 2, conductor 21, (see Fig. 5), the pick-up winding 17 of relay KR2 at location E, conductor 36, front contact 5 of device CR, conductor 23, track rail 1, conductor 24 (Fig. 1), and conductor 37 back to the negative terminal of the battery AB.

As long as the track section D—E remains vacant the pick-up winding of detector relay KR2 is in this manner supplied with the recurring code step pulses of auxiliary energy from battery AB. In responding to each of these pulses, it completes at contact 15 an energizing circuit for the slow release approach relay AR, which circuit may be traced from the positive terminal of a suitable supply source through front contact 16 of relay KR2, conductor 41, and the winding of relay AR back to the negative terminal of the supply source.

In the arrangement of Fig. 5, these recurring code step pulses of energy for relay AR are supplemented by interposed energizing pulses supplied over the second circuit before described as including conductor 51. This circuit is set up by front contact 50 of relay AR when picked up, and is completed each time that contact 19 of coding device CR occupies the lowermost or "on" 75

period position for the signal control code from battery TB. This supplementary circuit may be traced from the positive terminal of a suitable supply source through back contact 19 of device CR, conductor 51, front contact 50 of relay AR, conductor 53 and the winding of relay AR back to the negative terminal of the supply source.

Due to its slow releasing characteristics which are sufficient to bridge the longest interval between recurrent pulses of energization supplied over the two circuits just described, the approach relay AR holds its contacts 9 and 11 continuously picked up under the stated conditions and thereby renders inactive the wayside signal Se and the cab signal supply circuit involving source B-C.

In the event that a train comes into the track section at the rear of location E, the usual shunting action of its wheels and axles continuously energizes the operating winding of relay TR (see Fig. 1) and causes that relay to stay released. The presence of the train within the section also cuts off the supply of auxiliary energy to the pick-up winding 17 of detector relay KR2. That relay also stays continuously released and the supply of recurring pulses of energy to the winding of the slow release approach relay AR over contact 15 is accordingly discontinued.

Even though this approach relay AR should receive (which it ordinarily will not) one or more interposed energizing pulses over contact 19 of coding device CR during the "on" period of the trackway code cycle which follows, it will not remain picked up because such succeeding interposed pulses are more widely spaced than the interval of release delay for which relay AR is designed. Not being able to span the interval between consecutive released positions of coding device contact 19, the approach relay AR releases and breaks the second energizing circuit at contact 50 before the succeeding "on" code period occurs. Contact 9 of relay AR now completes a lighting circuit for the active lamp at the wayside signal Se and companion contact 11 connects the track transformer TT with the cab signal source B-C. The primary supply circuit now completed for the transformer is a duplicate of that shown in Fig. 4.

Each time, now, that coding contact 5 occupies the lowermost position the secondary winding of the transformer TT supplies alternating current energy to the track rails over a circuit which may be traced from the upper terminal of the transformer secondary through the track battery TB, impedance 22, coding contact 5, conductor 23, the track rail 1, the train wheels and axles (not shown), rail 2, and the conductor 27 back to the lower terminal of the transformer secondary. This coded alternating energy is effective for controlling train carried cab signals.

When the rear of the departing train clears the exit end location E the rails 1 and 2 again transmit coded direct current energy from battery TB to the track relay TR at the entrance location D (Fig. 1). That relay resumes its code following response, code step pulses of auxiliary energy of battery AB are again supplied to the rails and by them transmitted to the detector relay KR2, that relay resumes its code following response, the approach relay AR is once more picked up, and the approach controlled signalling functions are by it restored to their normally inactive state in which they continue until track section D-E once becomes occupied.

From the foregoing it will be seen that the facilities of Fig. 5 are effective to detect the absence

of received auxiliary energy within the space of a single code cycle. This is because the approach relay AR1 requires that energizing pulses alternately be supplied over contact 15 of relay KR2 and contact 19 of coding device CR to maintain its contacts in the picked-up position. As has been explained, the absence of a single one of either of the two types of pulses produces a gap greater than the release delay period for the relay AR and thus causes it to release. In this manner the response of the relay to a shunting of the track circuit is so quickened that cab signal flips at block joints are effectively prevented at all times.

Referring now to Fig. 6, I have represented a modified form of exit end apparatus which also produces the result just stated. In many respects it is identical with the arrangement of Fig. 5 and differs therefrom chiefly in utilizing a code following detector relay KR3 which has a slight delay in its release and also in using an added relay KA for aiding this detector relay in controlling the approach relay AR1. This added relay KA is provided with a pick-up circuit which includes back contact 19 of coding device AR and a front contact 55 of relay KR3 and with a stick circuit which includes the same back contact 19 and a front contact 56 of device KA. This added relay KA, moreover, is provided with a control contact 57 which is connected in parallel with the detector relay contact 15 in the energizing circuit for the approach relay AR1.

That relay AR1 may be a duplicate of the correspondingly identified device shown in the system of Fig. 5. It has a release delay period of the reduced order already described in connection with that earlier figure and is provided with contacts 9 and 11 which, through circuits not reproduced in Fig. 6, control the energization of the wayside signal Se and the facilities for supplying coded cab signal control energy to the rear track circuit.

From the track rails 1 and 2 down to and including the stick circuit (shown as including conductor 58) of the detector relay KR3, the apparatus of Fig. 6 is substantially a duplicate of that shown in Fig. 5. Up to this point the Fig. 6 equipment operates in the same manner as does the Fig. 5 apparatus. That is, each pulse of auxiliary energy received from the rails picks up relay KR3 and completes at contact 15 the energizing circuit for the approach relay AR1. The action of the added relay KA, however, is distinctive and will now be described.

This added relay KA is a code following device. Each time that detector relay KR3 is picked up by a pulse of auxiliary energy received from the trackway it completes its own stick circuit at contact 16. This circuit may be traced from the positive terminal of a suitable supply source through front contact 19 of the coding relay CR, front contact 16 of relay KR3, conductor 58, and the stick winding 18 of the detector relay back to the negative terminal of the supply source. As in the case of the earlier described figures, the effect of the stick circuit is to maintain the relay KR3 picked up until the end of the "off" period of the signal control code within which that pick-up occurs.

As already mentioned, the detector relay KR3 of Fig. 6 is made slightly slow in releasing in order that coding device contact 19 may return to the lowermost or "on" code position before contact 55 of relay KR3 drops out. Under this condition, the added relay KA is picked up over

a circuit which extends from the positive supply terminal through back contact 19 of relay CR, conductor 60, front contact 55 of relay KR3, conductor 61, and the winding of relay KA back to the negative supply terminal.

Once picked up, relay KA locks itself in over its referred to stick circuit which may be traced from the positive supply terminal through back contact 19 of device CR, conductor 62, front contact 56 of relay KA, conductor 61 and the winding of relay KA back to the negative supply terminal. This stick circuit remains completed until the end of the "on" code period at which time contact 19 of device CR moves upwardly and breaks the circuit, thereby allowing the added relay KA to release.

In the manner just explained, relay KA picks up at the beginning of each of the "on" code periods produced by device CR and releases at the end of the period. Contact 51 of device KA is thus caused to complete for the slow release relay AR1 its supplementary energizing circuit which may be traced from the positive terminal of a suitable supply source through front contact 51 of relay KA, conductor 41 and the winding of relay AR1 back to the negative supply terminal.

From the foregoing it will be seen that as long as the track section to the rear of location E remains vacant the apparatus of Fig. 6 is effective to supply relay AR1 with a pulse of pick-up energization during each of the "off" code periods produced by device CR and also with a pulse of supplemental or hold-up energization during each of the "on" periods of that code. In this manner the relay AR1 is enabled to hold its contacts 9 and 11 continuously picked up when the release period for this relay is reduced to the comparatively low value already described.

In the event that a train comes into the track section to the rear of location E, the code following operation of the detector relay KR3 immediately ceases, the energizing pulse normally supplied to the approach relay AR1 over contact 15 is omitted during the first cycle of the signal control code which follows entry of the train into the section and the relay AR1 accordingly releases because its delay release period is insufficient to bridge the time until the next "on" period of the code occurs.

Referring to Fig. 7, I have there shown a still further modified form of apparatus for detecting the absence of received auxiliary energy within the space of a single code cycle. The representation of Fig. 7 is only partial and in considering it it will be appreciated that it is intended for use with the complete exit end facilities which are shown in Figs. 5 and 6 and which cooperate with entrance end facilities of the character represented at location D in Fig. 1.

As in the system of Fig. 6, use is made of an added relay KA1. This may be a duplicate of the relay KA of Fig. 6 with the exception that it is arranged to have slow releasing characteristics. The code following detector relay KR3 of Fig. 7 is made slightly slow releasing as in the system of Fig. 6. Similarly, the approach relay AR1 has a comparatively short release delay period and in other respects may be a duplicate of the correspondingly identified device of Figs. 5 and 6.

In operation of the equipment of Fig. 7, each response by the detector relay KR3 to a pulse of auxiliary energy received from the track rails causes contact 15 to complete for the approach relay AR1 an energizing circuit which is a dupli-

cate of that shown in Fig. 6 and which may be traced from the positive terminal of a suitable supply source through conductor 64, front contact 15 of relay KR3, conductor 41 and the winding of relay AR1 back to the negative terminal of the supply source. At the same time contact 16 completes for the detector relay KR3 a stick circuit which may be traced from the positive supply terminal through front contact 16, conductor 39, front contact 19 of the coding device CR and the stick winding 18 of the relay back to the negative supply terminal.

In this manner, the winding of the approach relay AR1 is supplied with a pulse of energy during the full continuance of each of the "off" periods of the main signal control code which device CR produces.

Each time that the contacts of this device CR are in the lowermost or "on" code period positions, the added relay KA1 is picked up over a circuit which may be traced from the positive terminal of a suitable supply source through front contact 16 of detector relay KR3, conductor 39, back contact 19 of device CR, conductor 61 and the winding of relay KA1 back to the negative terminal of the supply source. The circuit just traced is completed at the beginning of each of the "on" code periods mentioned and it continues until the period of release delay for relay KR3 has expired.

Each time that relay KA1 is thus picked up, contact 51 thereof completes for the winding of the approach relay AR1 an energizing circuit which is the same as that traced during the description of Fig. 6. This circuit remains completed for the full duration of the release delay period of the added relay KA1. Preferably this delay is so chosen that the circuit is interrupted only just before the end of each of the "on" periods of the highest speed code which the signalling system employs.

From the foregoing it will be seen that under conditions of track section vacancy the apparatus of Fig. 7 operates to supply the approach relay AR1 with a separate pulse of energizing current during each of the "on" periods and during each of the "off" periods of the signal control code which device CR produces. In consequence, relay AR1 is enabled to hold up its contacts 9 and 11 continuously picked up even though the period of its release delay is of a comparatively low order.

Upon entry of a train into the track section with the rails of which conductors 23 and 27 of Fig. 7 are connected, the detector relay KR3 immediately ceases its code following operation, contact 15 thereof causes a pulse of energy for relay AR1 to be omitted during the "off" period of the first cycle of code which occurs following the entry of the train into the section, and relay AR1 releases its contacts before the next "on" code period occurs. In this manner the absence of received auxiliary energy is detected within the space of a single code cycle.

Referring to Fig. 8, I have there represented a still further modified form of apparatus for achieving the result just stated. There, use is made of an added relay KA2 which is provided with separate pick-up and stick windings 66 and 67. This relay may be of the quick releasing code following type. Use also is made of a code following detecting relay KR3 which has release delay characteristics of the small order explained in connection with Figs. 6 and 7. The approach relay AR1 is controlled in a manner identical

with that explained in connection with these same figures and it preferably has delay release characteristics of the comparatively low order previously described.

- 5 In operation of the apparatus of Fig. 8, each time that the detector relay KR3 responds to a pulse of auxiliary energy received over conductors 23 and 27 from the track rails (not shown), contact 16 completes the relay stick circuit and thus insures that the pick-up condition will be maintained until the end of the "off" code period. At the same time, contact 15 completes the before traced energizing circuit for the slow release approach relay AR1.
- 15 At the beginning of the succeeding "on" period in the code produced by device CR, contact 19 of that device picks up the added relay KA2 over a circuit which may be traced from the positive supply terminal through front contact 16 of relay KR3, conductor 39, back contact 19 of device CR, conductor 61, and the pick-up winding 66 of relay KA2 back to the negative supply terminal.

As in the case of Fig. 7, relay KR3 is provided with release delay characteristics which enable it to remain picked up for a short time following the beginning of each "on" code period. At the beginning of each of these "on" periods moreover, contact 68 of the device CR completes for the relay KA2 a stick circuit which may be traced from the positive terminal of a suitable supply source through a front contact 69 of the relay KA2, conductor 70, back contact 68 of relay CR, conductor 71 and the stick winding 67 of relay KA2 back to the negative supply terminal.

35 This stick circuit holds relay KA2 picked up during the full continuance of each of the "on" periods of the trackway codes produced by device CR. As a result contact 57 of relay KA2 causes the winding of the approach relay AR1 to be supplied with energizing current during each of these "on" periods over a circuit previously traced connection with Figs. 6 and 7 as including conductor 41.

45 From the foregoing it will be seen that during vacant conditions of the track section the apparatus of Fig. 8 functions to supply the approach relay AR1 with energizing current during each of the "on" and the "off" periods of the main signal control code which device CR produces.

50 In this manner the approach relay is enabled to hold its contacts 9 and 11 continuously picked up even though the period of its release delay is of the comparatively low order already described.

55 In the event that a train enters the section to the rails of which conductors 23 and 27 of Fig. 8 are connected, the detector relay KR3 immediately ceases its code following response and contact 15 thereof causes the pulse of energy normally supplied to the approach relay AR1 to be omitted during the first "off" period of the code cycle which follows the entry of the train into the section. Because of its short period release delay, the relay AR1 now drops out and in this manner the absence of received auxiliary energy is detected within the space of a single code cycle.

70 Referring finally to Fig. 9, the equipment there represented is also capable of producing the result just stated. It is similar to the apparatus of the immediately preceding figures and differs therefrom chiefly in its employment of an approach relay AR2 which is provided with two separate windings 73 and 74. At proper times 75 the first of these windings receives energizing

current over a circuit which includes back contact 19 of the coding device CR and one or the other of the contacts 15 and 57 of devices KR3 and KA. At other proper times the second winding of the approach relay is energized over front contact 19 of coding device CR and front contact 16 of detector relay KR3.

5 Aside from having the two separate windings the approach relay AR2 is similar to the device AR1 of the earlier described figures in that it is provided with a comparatively short period of contact release delay. The code following detector relay KR3 may be a duplicate of that of the correspondingly identified device of the earlier figures. The added relay KA is a quick 10 releasing code following device which may correspond to the relay KA of Fig. 6.

15 In operation of the equipment of Fig. 9, each time that the detector relay KR3 responds to a pulse of auxiliary energy received from the trackway, contact 16 thereof completes its own stick circuit (represented as including a conductor 30) and thereby assures that relay will remain picked up for the full continuance of the "off" code period. At the same time contact 15 20 of relay KR3 sets up for the winding 73 of the approach relay AR2 an energizing circuit which is completed by contact 19 of device CR at the beginning of the following "on" code period and which when so completed may be traced from the positive terminal of a suitable supply source through back contact 19, conductor 76, front contact 15 of relay KR3, conductor 77 and the winding 73 of relay AR2 back to the negative terminal of the supply source. As in the case of the 25 earlier described figures, relay KR3 is provided with a small amount of release delay in order that the circuit just traced may be completed in the manner described.

30 In this manner the approach relay AR2 is supplied with an energizing pulse at the beginning of each of the "off" periods of the main signal control code. Coincident with each of these pulses the added relay KA is picked up over a circuit which may be traced from the positive 35 supply terminal through back contact 19 of device CR, conductor 76, front contact 15 of detector relay KR3, conductors 77 and 78 and the winding of relay KA back to the negative supply terminal.

50 In picking up, contact 57 of relay KA completes for the winding 73 of the approach relay AR2 a supplementary energizing circuit which extends from the positive supply terminal through back contact 19 of device CR, conductor 76, front contact 55 57 of relay KA, conductors 78 and 77 and the winding 73 of relay AR2 back to the negative supply terminal. The added relay KA continues to remain energized and hence picked up for the full duration of the "on" 60 code period and in consequence contact 57 thereof maintains the just traced auxiliary energizing circuit for the approach relay AR2 completed until the end of the "on" code period.

65 Each time that relay KR3 effects the already described response to a pulse of auxiliary energy and picks up contact 16, there is completed for the second winding 74 of the approach relay AR2 an energizing circuit which may be traced from the positive supply terminal through front contact 19 of coding device CR, front contact 16 of relay KR3, conductor 79 and the winding 74 of relay AR2 back to the negative supply terminal. Once completed this circuit continues active for the full continuance of the "off" code 75

period and is interrupted only when contact 19 of coding device CR moves to the lowermost position to effect the beginning of the succeeding "on" period.

From the foregoing it will be seen that the equipment of Fig. 9 functions during conditions of track section vacancy to supply the approach relay AR2 with a pulse of energizing current during each of the "on" periods and during each of the "off" periods of the signal control code which coding device CR produces. Each of these energizing pulses, moreover, continues for the full duration of the particular code period within which it occurs and in this manner the approach relay AR2 is enabled to hold its contacts 9 and 11 continuously picked up even though the release delay period of the relay is exceedingly small.

In the event that a train comes into the track section with the rails of which conductors 23 and 27 of Fig. 9 are connected, the detector relay KR3 immediately discontinues its code following response and contacts 15 and 16 thereof occupy the lowermost position continuously. This causes winding 14 of the approach relay AR2 to remain continuously deenergized. Moreover, the winding 13 of relay AR2 likewise is continuously deenergized for the reason that the pick-up circuit for the added relay KA is interrupted at contact 15 and hence contact 57 is released. In consequence, the relay AR2 immediately releases contacts 9 and 11 and does this within the space of the first code cycle which follows the entry of the train into the track section.

From the foregoing it will be seen that I have made important improvements in that form of approach control without line wire scheme wherein the rails of each signal block length track transmit code step pulses of auxiliary energy forwardly from the block entrance to effect the energization of a slow release approach relay at the block exit as long as the block remains vacant.

In particular I have provided improved means for detecting these pulses at the exit end of each track circuit and for energizing the associated slow release approach delay in step with them; I have prolonged each period of this relay energization for the full duration of the signal code "off" period with which it coincides; I have so quickened the response of the approach relay to a shunting of the track circuit that cab signal flips at block joints are avoided; I have provided means for detecting the absence of received auxiliary energy within the space of a single code cycle; and I have accomplished all of the above through the use of circuit means of comparatively simple character.

As all of these improvements are entirely a function of the track circuit and apparatus which is directly associated therewith, they are independent of the coding and decoding facilities of the coded signaling system and hence are usable with a wide variety of different types and forms of such facilities.

While I have explained my invention in an application wherein both the lamps of the wayside signal and the supply of alternating current cab signal energy are approach controlled, it will be understood that either one of these functions may be performed separately and that other comparable functions may also be provided for in my new system.

Although I have herein shown and described only a few forms of approach control apparatus

embodying my invention, it is understood that various changes and modifications may be made therein within the scope of the appended claims without departing from the spirit and scope of my invention.

Having thus described my invention, what I claim is:

1. In combination with a section of track, means including a coding device at the section exit for supplying the rails of said section with coded signal control energy consisting of alternate "on" and "off" periods, means effective under vacant conditions of said section for further supplying said rails with a momentary pulse of auxiliary energy during each of said "off" code periods, a code following detector relay at the section exit provided with a pick-up circuit and with a stick circuit, means controlled by said coding device for connecting said pick-up circuit in energy receiving relation with said rails during said recurrent "off" code periods whereby as long as said track section remains vacant said detector relay receives said auxiliary energy pulses from those rails and is recurrently picked up thereby, means controlled by said coding device and by said detector relay for completing said stick circuit from the time of each pick-up of the detector relay until the end of the "off" code period within which that pick-up occurs whereby to prolong the hold-up time of that relay for the full duration of each of those "off" code periods, a slow release approach relay energized in step with the said recurrent pick-ups of said detector relay whereby to be maintained continuously picked up as long as said section is vacant and to release only when a train comes into the section, and traffic governing apparatus controlled by said approach relay.

2. In a railway signaling system which includes a section of track, the combination of means including a coding device at the section exit for supplying the rails of said section with track circuit energy in the form of alternate "on" and "off" periods that recur rapidly at times to constitute a fast code and more slowly at other times to constitute a slow code, means effective at the beginning of each "off" period of the said coded energy which is received from said rails for further supplying those rails with a pulse of auxiliary energy of an unvarying length fixed at less than the "off" period length of said fast code, a code following detector relay located at the section exit and provided with a pick-up circuit and with a stick circuit, means controlled by said coding device for connecting said pick-up circuit in energy receiving relation with said rails during said "off" code periods whereby as long as said track section remains vacant said detector relay receives said auxiliary energy pulses from those rails and is recurrently picked up thereby, means controlled by said coding device and by said detector relay for completing said stick circuit from the time of each pick-up of the detector relay until the end of the "off" code period within which that pick-up occurs whereby to prolong the hold-up time of that relay for the full duration of each of those "off" periods, a slow release approach relay energized in step with the said recurrent pick-ups of said detector relay whereby to be maintained continuously picked up as long as said section is unoccupied, and traffic governing apparatus controlled by said approach relay and rendered active when that relay releases in response to the presence of a train in said section.

3. In combination, a section of railway track,

- means including a coding device at the section exit for supplying the rails of said section with track circuit energy in the form of alternate "on" and "off" periods that recur rapidly at times to constitute a fast code and more slowly at other times to constitute a slow code, a code following track relay connected with said rails and operated by the said coded energy which is received therefrom, means controlled by said track relay and effective at the beginning of each "off" period of the received track circuit code to supply said rails with a pulse of auxiliary energy of an unvarying length fixed at less than the "off" period length of said fast code, a code following detector relay at the section exit provided with a pick-up circuit and with a stick circuit, means controlled by said coding device for connecting said pick-up circuit in energy receiving relation with the section rails during each of the said "off" code periods whereby as long as said track section remains vacant said detector relay receives said auxiliary energy pulses from those rails and is recurrently picked up thereby, means controlled by said coding device and by said detector relay for completing said stick circuit from the time of each pick-up of the detector relay until the end of the "off" code period within which that pick-up occurs whereby to prolong the hold-up time of that relay for the full duration of each of those "off" periods, a slow release approach relay energized in step with the said recurrent pick-ups of said detector relay whereby to be maintained continuously picked up as long as said section is vacant and to release only when a train comes into the section, and traffic governing apparatus controlled by said approach relay.
4. In combination, a section of railway track, a source of trackway energy for the rails of said section, a continuously operating coding device at the section exit which includes a coding contact, means including said contact for recurrently connecting said source to said rails whereby to produce a trackway code consisting of alternate "on" and "off" periods, means effective under vacant conditions of said section for further supplying a momentary pulse of auxiliary energy to said rails during each of said "off" code periods, a code following detector relay installed at the section exit and provided with a pick-up circuit and with a stick circuit, means including the aforesaid coding contact for connecting said pick-up circuit in energy receiving relation with said rails during each of said "off" code periods whereby as long as said track section remains vacant said detector relay receives and is recurrently picked up by said auxiliary energy, means controlled by said coding device and by said detector relay for completing said stick circuit from the time of each pick-up of the detector relay until the end of the "off" code period within which that pick-up occurs whereby to prolong the hold-up time of that relay for the full duration of each of those "off" periods, a slow release approach relay, means controlled by said detector relay for energizing said approach relay in step with the said recurrent pick-ups of the detector relay whereby to maintain the approach relay continuously picked up as long as said section is vacant and to allow that relay to release only when a train comes into the section, and traffic governing apparatus controlled by said approach relay.
5. In combination with a section of railway track, a source of trackway energy and a code

following detector relay at the section exit, a continuously operating coding contact which repeatedly connects the rails of said section first to said trackway energy source and then to the winding of said detector relay and thereby produces a trackway code consisting of alternate "on" and "off" periods the latter of which coincide with said relay winding connections, a code following track relay connected with said rails and operated by the said coded energy which is received therefrom, means controlled by said track relay for supplying auxiliary energy to said rails during each of the said "off" periods of the said received trackway code whereby as long as said track section remains vacant said detector relay receives said auxiliary energy from those rails and is recurrently picked up thereby, a slow release approach relay, means controlled by said detector relay for energizing said approach relay in step with the said recurrent pick-ups of the detector relay whereby to maintain the approach relay continuously picked up under vacant conditions of said section and to allow that relay to release only when said section becomes occupied, and traffic governing apparatus controlled by said approach relay.

6. In combination with a section of track which forms a part of a railway signaling system of the coded track circuit class, approach control facilities comprising a source of track circuit energy at the exit end of the section, a code following detector relay also located at the section exit and provided with a pick-up circuit and with a stick circuit, a similarly located coding device having a contact which repeatedly connects the rails of said section first to said trackway energy source and then to said pick-up circuit and thereby produces a trackway code consisting of alternate "on" and "off" periods the latter of which coincide with said pick-up circuit connections, a code following track relay connected with said rails and operated by the said coded energy which is received therefrom, a source of auxiliary energy, means controlled by said track relay for momentarily connecting said rails to said auxiliary source each time that the track relay releases whereby during each of the said "off" periods of the received trackway code those rails receive a short pulse of auxiliary energy which they transmit forwardly to the said pick-up circuit of said detector relay and thereby cause that relay recurrently to pick up as long as said section remains vacant, a local source of stick energy for the detector relay, means controlled by said coding device and by said detector relay for connecting said local source to the said stick circuit of the detector relay from the time of each pick-up of that relay until the end of the "off" code period within which that pick-up occurs whereby to prolong the hold-up time of the detector relay for the full duration of each of those "off" periods, a slow release approach relay, means controlled by said detector relay for energizing said approach relay in step with the responses of the detector relay whereby to maintain the approach relay continuously picked up as long as said section is vacant and to allow that relay to release only when a train comes into the section, and traffic governing apparatus controlled by said approach relay.

7. In combination with a section of railway track, means including a coding device at the section exit for supplying the section rails with signal control energy in the form of alternate

"on" and "off" periods that recur rapidly at times to constitute a fast code and more slowly at other times to constitute a slow code, a code following detector relay also at the section exit 5 provided with a pick-up circuit and with a stick circuit, means including a contact of said coding device for connecting said pick-up circuit in energy receiving relation with said rails during each of the said "off" code periods, means effective at the beginning of each "off" period of the 10 said coded energy which is received from said rails for further supplying those rails with a pulse of auxiliary energy of an unvarying length fixed at less than the "off" period length of said fast code whereby recurrently to excite the said 15 pick-up circuit of said detector relay and thereby cause that relay recurrently to pick up as long as said section remains vacant, means controlled by said coding device and by said detector relay for completing the said stick circuit of the 20 detector relay from the time of each pick-up of that relay until the end of the "off" code period within which that pick-up occurs whereby to prolong the hold-up time of the detector relay for the full duration of each of those "off" periods, a slow 25 release approach relay energized in step with the said recurrent pick-ups of said detector relay whereby to be maintained continuously picked up as long as said section is vacant and to release only when a train comes into the section, and traffic governing apparatus controlled by said approach relay.

8. In combination with a section of railway track, a source of trackway energy at the section exit, a code following detector relay also located at the section exit and provided with a pick-up circuit and with a stick circuit, a similarly located coding device having a contact which repeatedly connects the rails of said track section first to said energy source and then to said relay pick-up circuit and thereby produces a trackway code consisting of alternate "on" and "off" periods the latter of which coincide with said pick-up circuit connections, means for further supplying said rails with auxiliary energy whereby momentarily to excite the said pick-up circuit of said detector relay at the beginning of each of said "off" code periods and thereby cause that relay recurrently to pick up as long as said section remains vacant, means controlled by said coding device and by said detector relay for completing said relay stick circuit from the time of each pick-up of the detector relay until the end of the said "off" code period within which that pick-up occurs whereby to prolong the hold-up time of that relay for the full duration of each of those "off" periods, a slow release approach relay, means controlled by said detector relay for energizing said approach relay in step with the said recurrent pick-ups of the 45 detector relay whereby to maintain the approach relay continuously picked up under vacant conditions of said section and to allow that relay to release only when said section becomes occupied, and traffic governing apparatus controlled by said 50 approach relay.

9. In combination with a section of railway track, means including a coding device at the section exit for supplying the rails of said section with coded signal control energy consisting of alternate "on" and "off" periods, a code following detector relay also located at the section exit and provided with a pick-up circuit and with a stick circuit, means including a contact of said coding device for connecting said pick-up circuit across 55 said rails during each of said "off" code periods,

means controlled by the said coded energy which is received from said rails for further supplying those rails with a pulse of auxiliary energy of momentary length at the beginning of each "off" period of the received code whereby recurrently to excite the said pick-up circuit of said detector relay and thereby cause that relay recurrently to pick up as long as said section remains vacant, a source of stick energy, means including a front contact of said detector relay and a contact of 10 said coding device that is closed during the "off" periods of said signal control code for connecting the said stick circuit of said detector relay to said stick energy source from the time of each pick-up of the detector relay until the end of the said "off" code period within which that pick-up occurs whereby to prolong the hold-up time of that relay for the full duration of each of those "off" periods, a slow release approach relay energized in step with the said recurrent pick-ups of the 15 detector relay whereby to be maintained continuously picked up as long as said section is vacant and to release only when a train comes into the section, and traffic governing apparatus controlled by said approach relay.

10. In combination with a section of railway track, approach control facilities comprising means including a coding device at the section exit for supplying the rails of the section with coded signal control energy consisting of alternate "on" and "off" periods, a code following detector relay also at the section exit, means controlled by said coding device for connecting the winding of said relay in energy receiving relation with said rails during each of the said "off" periods of said signal control code and for interrupting that connection during the "on" periods of that code, means for further supplying said section rails with auxiliary energy whereby to excite said detector relay during said "off" code periods and thereby cause that relay recurrently to pick up as long as said section remains vacant, a slow release approach relay, means controlled by said detector relay for energizing said approach relay in step with the said recurrent pick-ups of the 40 detector relay whereby to maintain the approach relay continuously picked up under vacant conditions of said section and to allow that relay to release only when said section becomes occupied, and traffic governing apparatus controlled by said 45 approach relay.

11. In a railway signaling system which includes a section of track, the combination of means including a coding device at the section exit for supplying the rails of said section with coded signal control energy consisting of alternate "on" and "off" periods, a code following track relay connected with said rails and operated by the said coded energy which is received therefrom, means controlled by said track relay for supplying said rails with a momentary pulse of auxiliary energy at the beginning of each of the said "off" periods of the received signal control code, a code following detector relay located at the section exit and provided with a pick-up winding 60 and with a stick winding, means controlled by said coding device for connecting said pick-up winding across said rails during each of the said "off" periods of said signal control code whereby as long as said track section remains vacant said 65 detector relay receives said pulses of auxiliary energy from those rails and is recurrently picked up thereby, a source of stick energy, means controlled by said coding device and by said detector relay for connecting said stick winding to said 70

75

- stick energy source from the time of each pick-up of the detector relay until the end of the "off" code period within which that pick-up occurs whereby to prolong the hold-up time of that relay 5 for the full duration of each of those "off" periods, a slow release approach relay energized in step with the said recurrent pick-ups of the detector relay whereby to be maintained continuously picked up under vacant conditions of said section 10 and to release only when said section becomes occupied, and traffic governing apparatus controlled by said approach relay.
12. In combination with a section of railway track, a source of trackway energy at the section 15 exit, a similarly located code following detector relay having a pick-up winding and a stick winding, a continuously operating coding device also at the section exit, means including a contact of said device for repeatedly connecting the rails 20 of said track section first to said trackway energy source and then to said pick-up winding of the detector relay whereby to produce a trackway code consisting of alternate "on" and "off" periods the latter of which coincide with said pick-up 25 winding connections, means controlled by the said coded energy which is received from said rails for further supplying those rails with a pulse of auxiliary energy of momentary length at the beginning of each "off" period of the received 30 code whereby to excite said pick-up winding during those "off" periods and cause said detector relay recurrently to pick up as long as said section remains vacant, a source of stick energy, means including a contact of said coding device 35 and a contact of said detector relay for connecting the said stick winding of that relay to said stick energy source from the time of each pick-up of the detector relay until the end of the said "off" code period within which that pick-up occurs whereby to prolong the hold-up time of that 40 relay for the full duration of each of those "off" code periods, a slow release approach relay, means controlled by said detector relay for energizing said approach relay in step with the said recurrent pick-ups of the detector relay whereby to maintain the approach relay continuously picked up 45 as long as said section is vacant and to allow that relay to release only when a train comes into the section, and traffic governing apparatus controlled by said approach relay.
13. In combination with a section of railway track, approach control facilities comprising a source of trackway energy at the section exit, a similarly located code following detector relay 50 provided with a pick-up winding and with a stick winding, a continuously operating coding device also at the section exit, means including a contact of said device for repeatedly connecting the rails of said track section first to said trackway energy source and then to said relay pick-up winding whereby to produce a trackway code consisting of alternate "on" and "off" periods the latter of which coincide with said pick-up winding connections, means for further supplying said rails with auxiliary energy whereby to excite said pick-up 55 winding during said "off" code periods and thereby cause said detector relay recurrently to pick up as long as said section remains vacant, a source of stick energy, means including a contact of 60 said coding device and a contact of said detector relay for connecting the said stick winding of that relay to said stick energy source from the time of each pick-up of the detector relay until the end of the said "off" code period within which that pick-up occurs whereby to prolong the hold-up time of that relay for the full duration of each of said "off" code periods, a slow release approach relay, a circuit completed over a front contact of said detector relay for energizing the winding of said 65 approach relay in step with the said recurrent pick-ups of the detector relay whereby to maintain the approach relay continuously picked up as long as said section is vacant and to allow that relay to release only when a train comes into 70
- 75 that pick-up occurs whereby to prolong the hold-

up time of that relay for the full duration of each of said "off" code periods, a slow release approach relay, means controlled by said detector relay for energizing said approach relay in step with the said recurrent pick-ups of said detector relay whereby to maintain the approach relay continuously picked up under vacant conditions of said section and to allow that relay to release only when said section becomes occupied, and traffic governing apparatus controlled by said approach 10 relay.

14. In combination, a section of track, means including a coding device at the section exit for supplying the rails of said section with coded signal control energy consisting of alternate "on" and "off" periods, a code following detector relay 15 also located at the section exit and having a pick-up circuit and a stick circuit, means controlled by said coding device for connecting said pick-up circuit in energy receiving relation with 20 said rails during each "off" period of the signal control code, means for further supplying said section rails with auxiliary energy whereby to excite said pick-up circuit during said "off" code periods and thereby cause said detector relay recurrently to pick up as long as said section 25 remains vacant, means controlled by said coding device and by said detector relay for completing said stick circuit from the time of each pick-up of the detector relay until the end of the said 30 "off" code period within which that pick-up occurs whereby to prolong the hold-up time of that relay for the full duration of each said "off" code periods, a slow release approach relay, means including a transformer excited over a direct 35 current circuit controlled by a contact of said detector relay for energizing the winding of said approach relay in step with the said recurrent pick-ups of the detector relay whereby to maintain the approach relay continuously picked up 40 as long as said section is vacant and to allow that relay to release only when a train comes into the section, and traffic governing apparatus controlled by said approach relay.

15. In combination, a section of track, means 45 including a coding device at the section exit for supplying the rails of said section with coded signal control energy consisting of alternate "on" and "off" periods, a code following detector relay also located at said section exit and having a 50 pick-up circuit and a stick circuit, means controlled by said coding device for connecting said pick-up circuit in energy receiving relation with said rails during each "off" period of the signal control code, means for further supplying said 55 section rails with auxiliary energy whereby to excite said pick-up circuit during said "off" code periods and thereby cause said detector relay recurrently to pick up as long as said section remains vacant, means controlled by said coding device and by said detector relay for completing said stick circuit from the time of each pick-up of the detector relay until the end of the said 60 "off" code period within which that pick-up occurs whereby to prolong the hold-up time of that relay for the full duration of each of said "off" code periods, a slow release approach relay, a circuit completed over a front contact of said detector relay for energizing the winding of said 65 approach relay in step with the said recurrent pick-ups of the detector relay whereby to maintain the approach relay continuously picked up as long as said section is vacant and to allow that relay to release only when a train comes into 70

75

the section, and traffic governing apparatus controlled by said approach relay.

16. In combination with a section of railway track, approach control facilities comprising means including a coding device at the section exit for supplying the rails of the section with coded signal control energy consisting of alternate "on" and "off" periods, a code following detector relay also located at the section exit and having a single operating winding, means controlled by said coding device for connecting said relay winding in energy receiving relation with said rails during each of the said "off" periods of the said signal control code, means for further supplying the section rails with auxiliary energy whereby to excite said relay winding during said "off" code periods and thereby cause said detector relay recurrently to pick up as long as said section remains vacant, a local source of energy at said section exit, means controlled by said coding device and by said detector relay for connecting said relay winding with said local source from the time of each pick-up of the detector relay until the end of the said "off" code period within which that pick-up occurs whereby to prolong the hold-up time of that relay for the full duration of each of said "off" code periods, a slow release approach relay, means controlled by said detector relay for energizing said approach relay in step with the said recurrent pick-ups of the detector relay whereby to maintain the approach relay continuously picked up under vacant conditions of said section and to allow that relay to release only when said section becomes occupied, and traffic governing apparatus controlled by said approach relay.

17. In combination with a section of railway track, approach control facilities comprising a source of trackway energy at the section exit, a similarly located code following detector relay provided with a single operating winding, a continuously operating coding device also at the section exit, means including contacts of said device for connecting the rails of said track section first to said trackway energy source and then to said relay winding whereby to produce a trackway code consisting of alternate "on" and "off" periods the latter of which coincide with said relay winding connections, means for further supplying said rails with auxiliary energy whereby to excite said relay winding during said "off" code periods and thereby cause said detector relay recurrently to pick up as long as said section remains vacant, a local source of stick energy for said relay, means including a contact of said coding device and a contact of said detector relay for connecting said winding of that relay to said local source from the time of each pick-up of the detector relay until the end of the said "off" code period within which that pick-up occurs whereby to prolong the hold-up time of that relay for the full duration of each of said "off" code periods, a slow release approach relay, means controlled by said detector relay for energizing said approach relay in step with the said recurrent pick-ups of the detector relay whereby to maintain the approach relay continuously picked up under vacant conditions of said section and to allow that relay to release only when said section becomes occupied, and traffic governing apparatus controlled by said approach relay.

18. In a railway signaling system, the combination with a section of track of means including a coding device at the section exit for supplying the rails of said section with coded

track circuit energy consisting of alternate "on" and "off" periods, a code following track relay connected with said rails and operated by the said coded energy which is received therefrom, means controlled by said track relay for supplying said rails with a pulse of auxiliary energy during each of the said "off" periods of the received track circuit code, a code following detector relay at the section exit, means for connecting said detector relay in energy receiving relation with said rails during each of said "off" code periods whereby as long as said track section remains vacant said detector relay receives said pulses of auxiliary energy from the rails and is recurrently picked up thereby, a slow release approach relay, means controlled by said detector relay for energizing said approach relay in step with the said recurrent pick-ups of the detector relay whereby to maintain the approach relay continuously picked up as long as said section is vacant and to allow that relay to release when and only when a train comes into the section, means for also energizing said approach relay during the said "on" periods of the signal control code providing said detector relay is receiving and responding to said auxiliary energy during successive "off" periods of that code whereby to reduce the time of release delay which said approach relay must have in order to stay continuously picked up under said vacant track section conditions, and traffic governing apparatus controlled by said approach relay.

19. In combination with a section of railway track, approach control facilities comprising means including a coding device at the section exit for supplying the rails of the section with coded signal control energy consisting of alternate "on" and "off" periods, a code following detector relay also at said section exit, means controlled by said coding device for connecting said relay in energy receiving relation with said rails during each of the said "off" periods of said signal control code, means for further supplying said section rails with auxiliary energy whereby to excite said detector relay during said "off" code periods and thereby cause that relay recurrently to pick up as long as said section remains vacant, a slow release approach relay, a circuit for energizing said approach relay in step with the said "off" period pick-ups of said detector relay whereby to maintain the approach relay continuously picked up as long as said section is vacant and to allow that relay to release only when the section becomes occupied, a circuit for also energizing said approach relay during the said "on" periods of said signal control code provided said detector relay is receiving and responding to said auxiliary energy during successive "off" periods of that code whereby to reduce the time of release delay which said approach relay must have in order to stay continuously picked up under said vacant track section conditions, and traffic governing apparatus controlled by said approach relay.

20. In combination with a section of railway track, approach control facilities comprising means including a coding device at the section exit for supplying the rails of the section with coded signal control energy consisting of alternate "on" and "off" periods, a code following detector relay also located at the section exit and provided with a pick-up circuit and with a stick circuit, means controlled by said coding device for connecting said pick-up circuit in energy receiving relation with said rails during each of the

- said "off" periods of said signal control code, means for further supplying the section rails with auxiliary energy whereby to excite said pick-up circuit during said "off" code periods and thereby cause said detector relay recurrently to pick up as long as said section remains vacant, means controlled by said coding device and by said detector relay for completing said stick circuit from the time of each of said pick-ups of the detector relay until the end of the said "off" code period within which the pick-up occurs whereby to prolong the hold-up time of that relay for the full duration of each of said "off" code periods, a slow release approach relay, means for energizing said approach relay in step with the pick-ups of said detector relay whereby to maintain the approach relay continuously picked up as long as said section is vacant and to allow that relay to release only when the section becomes occupied, means for also energizing said approach relay during the said "on" periods of said signal control code provided said detector relay is receiving and responding to said auxiliary energy during successive "off" periods of that code whereby to reduce the time of release delay which said approach relay must have in order to stay continuously picked up under said vacant track section conditions, and traffic governing apparatus controlled by said approach relay.
21. In combination with a section of railway track, approach control facilities comprising a source of trackway energy at the section exit, a similarly located code following detector relay, a continuously operating coding device also at the section exit which repeatedly connects the rails of said section first to said trackway energy source and then to the winding of said detector relay and thereby produces a trackway code consisting of alternate "on" and "off" periods the latter of which coincide with said relay winding connections, means for further supplying said rails with auxiliary energy whereby to excite said relay winding during said "off" code periods and thereby cause said detector relay recurrently to pick up as long as said section remains vacant, an added code following relay also installed at the section exit and also having a small release delay, a circuit for picking up said added relay over a front contact of said detector relay and a contact of said coding device that is closed during the said "on" periods of said trackway code, a slow release approach relay, a circuit for energizing said approach relay over a front contact of either or both of said detector and added relays whereby to maintain the approach relay continuously picked up as long as said section is vacant and to allow that relay to release only when the section becomes occupied, and traffic governing apparatus controlled by said approach relay.
22. In combination with a section of railway track, approach control facilities comprising a source of trackway energy at the section exit, a similarly located code following detector relay having a small release delay, a continuously operating coding device at the section exit which repeatedly connects the rails of said section first to said trackway energy source and then to the winding of said detector relay and thereby produces a trackway code consisting of alternate "on" and "off" periods the latter of which coincide with said relay winding connections, means for further supplying said rails with auxiliary energy whereby to excite said relay winding during said "off" code periods and thereby cause said detector relay recurrently to pick up as long as said section remains vacant, an added code following relay also installed at the section exit and provided with a pick-up winding and with a stick winding, a circuit for energizing said pick-up winding over a front contact of said detector relay and a contact of said coding device.
23. In combination with a section of railway track, approach control facilities comprising a source of trackway energy at the section exit, a similarly located code following detector relay having a slight release delay, a continuously operating coding device at the section exit which repeatedly connects the rails of said section first to said trackway energy source and then to the winding of said detector relay and thereby produces a trackway code consisting of alternate "on" and "off" periods the latter of which coincide with said relay winding connections, means for further supplying said rails with auxiliary energy whereby to excite said relay winding during said "off" code periods and thereby cause said detector relay recurrently to pick up as long as said section remains vacant, an added code following relay also installed at the section exit and also having a small release delay, a circuit for picking up said added relay over a front contact of said detector relay and a contact of said coding device that is closed during the said "on" periods of said trackway code, a slow release approach relay, a circuit for energizing said approach relay over a front contact of either or both of said detector and added relays whereby to maintain the approach relay continuously picked up as long as said section is vacant and to allow that relay to release only when the section becomes occupied, and traffic governing apparatus controlled by said approach relay.
24. In combination with a section of railway track, approach control facilities comprising a source of trackway energy at the section exit, a similarly located code following detector relay having a small release delay, a continuously operating coding device at the section exit which repeatedly connects the rails of said section first to said trackway energy source and then to the winding of said detector relay and thereby produces a trackway code consisting of alternate "on" and "off" periods the latter of which coincide with said relay winding connections, means for further supplying said rails with auxiliary energy whereby to excite said relay winding during said "off" code periods and thereby cause said detector relay recurrently to pick up as long as said section remains vacant, an added code following relay also installed at the section exit and provided with a pick-up winding and with a stick winding, a circuit for energizing said pick-up winding over a front contact of said detector relay and a contact of said coding device.

vice that is closed during the said "on" periods of said trackway code, a circuit for energizing said stick winding over another contact of said coding device that is closed during said "on" code periods and a front contact of said added relay, a slow release approach relay, a circuit for energizing said approach relay over a front contact of either or both of said detector and added relays whereby to maintain the approach relay continuously picked up as long as said section is vacant and to allow that relay to release only when the section becomes occupied, and traffic governing apparatus controlled by said approach relay.

5 25. In combination with a section of railway track, approach control facilities comprising a source of trackway energy at the section exit, a similarly located code following detector relay having a small release delay, a continuously operating coding device at the section exit which repeatedly connects the rails of said section first to said trackway energy source and then to the winding of said detector relay and thereby produces a trackway code consisting of alternate 10 "on" and "off" periods the latter of which coincide with said relay winding connections, means for further supplying said rails with auxiliary energy whereby to excite said relay winding during said "off" code periods and thereby cause

said detector relay recurrently to pick up as long as said section remains vacant, an added code following relay also at the section exit, a circuit for picking up said added relay over a front contact of said detector relay and a contact of said coding device that is closed during said "on" periods of said trackway code, a stick circuit for said added relay which is completed over said coding device contact and a front contact of the added relay, a slow release approach relay provided with two separate windings, a circuit for energizing one of said windings over a contact of said coding device that is closed during said "on" code periods and a front contact of either or both of said detector and added relays whereby to maintain the approach relay continuously picked up as long as said section is vacant and to allow that relay to release when and only when the section becomes occupied, a circuit for energizing the other of said approach relay windings over a front contact of said detector relay and a contact of said coding device that is closed during the said "off" periods of said trackway code whereby to reduce the time of release delay that said approach relay must have in order to stay continuously picked up under said vacant track section conditions, and traffic governing apparatus controlled by said approach relay.

EDWARD U. THOMAS.
